OIL STOVE BURNER MECHANISM

William T. Bradbury, Kankakee, Ill., assignor to
 Florence Stove Company, Gardner, Mass., a
 corporation of Massachusetts

Application September 29, 1934, Serial No. 746,176

7 Claims. (Cl. 158—42)

This invention relates to improvements in oil stoves and particularly to a so-called wickless type burner and the mechanism for operating the same.

5 Ordinarily, the wickless type of oil burner comprises a bowl having a relatively deep annular channel therein arranged to contain a supply of fuel for immediate combustion. The height of the flame produced by the burner is regulated by 10 varying the amount of fuel in the annular channel and this is generally accomplished by raising or lowering the burner bowl with reference to a constant level supply source of the fuel, the source and the bowl being, of course, suitably 15 connected. The ultimate aim of the invention is to provide an improved manually operable mechanism applied, in this instance, directly to the burner to effect a raising or lowering of the fuel level therein.

20 In prior devices of this character various expedients have been employed to control the raising and lowering of the burner, but disadvantageous features such as expensive construction, slow operation, inaccuracy of adjustment and 25 tilting due to strain have been inherent in many of these devices.

The primary object of the present invention, therefore, is to provide a new and improved means for adjusting the burner, which is inexpensive to 30 manufacture and positive and accurate in operation, and which is easily and conveniently operable to raise or lower the burner to any desired position within a defined range of movement and this with only a relatively small movement of 35 the operating handle.

A particular object of the invention is to provide operating means for a burner of the foregoing character employing few parts of a simple and inexpensive character.

40 Another object is to provide a burner mechanism of the foregoing character which is simply and compactly constructed and is efficiently arranged to permit ready assembly or disassembly as required.

45 Another object of the invention is to provide a burner mechanism which is characterized by ease of operation and durability of construction, and in which the pressure for raising and lowering the burner is so applied as to prevent tilting 50 or twisting of the burner bowl.

Other objects and advantages will become apparent in the following description of an exemplary form of the invention and from the accompanying drawing, in which:

55 Figure 1 is a sectional elevation through a por-

tion of a stove and showing details of construction of the improved burner mechanism.

Fig. 2 is a sectional plan view taken substantially on line 2—2 of Fig. 1.

Fig. 3 is a rear elevation, partly in section, of 5 the burner mechanism.

Although the invention is susceptible of various modifications and alternative constructions, I have shown and herein described in detail, the preferred embodiment, but it is to be understood 10 that I do not thereby intend to limit the invention to the specific form disclosed, but intend to cover all modifications and alternative constructions falling within the spirit and scope of the invention as expressed in the appended claims. 15

In the embodiment of the invention shown for purposes of illustration, 19 designates an annular burner bowl of trough-like formation mounted for independent movement vertically with respect to a fixed constant level supply (not shown) and 20 providing seats at its upper edges for the usual chimney unit (not shown). At one side the trough is connected by means of the usual telescoping pipe connection 12 with an elongated fuel supply pipe 13 extending longitudinally of the 25 stove body and disposed rearwardly of a front plate 14 which is rigid with and forms a part of the main supporting frame of the stove. To support the burner for vertical movements, I provide an upright standard 15 disposed centrally of the burner bowl and depending into a housing 16 coacting with the standard to guide the burner as the same is raised and lowered. The standard also forms a part of my improved raising and lowering means comprising generally a 30 pinion 17 fixed upon the rear end of an operating shaft 18 and coacting with a rack 19 carried by the standard, the forward end portion of the shaft being extended through the front plate 14 and provided with an operating handle 20. 35

The housing 16 is preferably in the form of a substantially rectangular open faced box-like structure formed of suitable sheet metal and comprises a main body plate 21 provided with laterally bent marginal upper and lower flanges 22 45 and 23, respectively, and side flanges 24 and 25, respectively. To connect the housing 16 to the stove framework, an L-shaped bracket 27 is connected by a bolt 28 to the flange 24 while a bolt 29 rigidly secures the bracket to the rear face of 50 the front plate 14. To guide the standard 15, which is preferably of channel-shape cross section, the flanges 22 and 23 of the housing are provided with aligned guide slots 30 and 31, respectively. These slots 30 and 31 are of a shape to 55

receive the standard 15 with only a slight clearance to permit the same to be slidably reciprocated therein, but preventing the standard from tilting.

- 5 At its upper end, the standard 15 is provided with a head 34 of substantially the same width as the inside dimensions of the bowl 10. The upper edge of the head 34 has an integral horizontal flange 35 which is secured diametrically across 10 the lower face of a flat perforated plate 37 rigid with the upper inner edge of the burner bowl 10. Lateral flanges 38 along the edges of the standard 15 follow the contours of the head 34 and are secured at their ends as by welding to the opposite lower edges of the bowl 10. Thus, the burner bowl is rigidly supported by the standard 15 and will be prevented from tilting or twisting relative to the standard due to accidental causes or from the weight of the superposed chimney 20 which is commonly supported full upon the bowl.

The weight of the burner bowl and standard is supported primarily by the pinion 17 through the rack 19, and a salient feature of the invention resides in the arrangement of the rack and pinion in substantially the center of the total gravitational and frictional forces which must be overcome in the operation of the device. To the accomplishment of this end, a longitudinal slot 40 is formed centrally of the body of the standard 15, and the rack 19 is formed as an integral part of one longitudinal edge of the slot. Preferably, the standard 15 is formed of suitable sheet metal and the slot 40 and rack 19 are cut by a simple stamping operation, the rack being adjacent that 35 edge of the standard which is nearest the extensible connection 12. This position of the rack 19 is preferred because the drag on the burner bowl 10 caused by the frictional contact of the packing in stuffing box 42 which is fitted about 40 the telescoping ends of the connection restrains the free raising or lowering movement of the bowl and shifts the center of operating force toward the one side away from the center of gravity of the bowl.

45 The pinion 17, which may be stamped from suitable sheet metal, is disposed within the slot 40 in the plane of the body of the standard 15 and has its axis at the center of gravity of the burner bowl and standard. Rotation of the shaft 18 by 50 means of the handle 20 will cause the pinion 17 to move the rack 19 up or down as desired, and the pinion will abut the upper or lower edges of the slot 40 at the extreme limits of movement to which the reciprocations of the standard must 55 be confined.

In the present instance it has been found desirable to provide a correlated relationship of the length of the slot 40 and the ratio of the rack and pinion teeth which will permit the full raising or 60 lowering of the burner by merely half a turn of the pinion 17. Hence, the handle 20 which is shown as a lever having an indicator point 44 at its upper end, need be manipulated only through an arc of 180° to cause movement of the burner 65 from one extreme limit to the other; and relatively small movements of the handle will rapidly shift the burner to the desired operative position. Because of arrangement of the pinion 17 in the plane of the body of the standard 15 overrunning of the pinion relative to the rack 19 will be 70 prevented thereby avoiding bending of the teeth. Thus, even though the teeth of the pinion and rack may not be formed with perfect accuracy due to the simple stamping operation by which 75 they are formed, yet because of the described

arrangement they will be maintained in proper meshed relationship at all times.

In order to maintain the shaft 18 in a fixed axial relationship relative to the housing 16, a fixed U-shaped bracket 46 is suitably apertured 5 to receive the inner end of the shaft and provide a bearing 47 adjacent the pinion 17. The ends of the bracket 46 are provided with laterally extending flanges 48 secured to the inner face of the body 21 of the housing as by means of spot 10 welds 49. Intermediate its ends the shaft 18 is supported by the housing body part 21 which is suitably apertured for the purpose and provides a bearing for the shaft. Consequently, while the weight of the burner bowl and standard is primarily supported by the pinion 17 and the shaft 18, the housing 16 will nevertheless carry this weight through the described bearings for the shaft.

I provide means for counteracting the weight 20 of the burner and standard so as to retain the pinion and shaft 18 at any given position to which they may be adjusted by manipulation of the handle 20, and, in the present instance, this means comprises a bowed flat spring 51 which is suitably apertured to freely receive the shaft. The ends of the spring 51 abut against the outer face of the housing body plate 21, while a collar 52 which is held in place on the shaft 18 by suitable means such as a cotter pin 53 provides an 30 abutment for the central portion of the spring. Substantial pressure is exerted by the spring against the collar 52 thereby forcing the shaft 18 to the right as viewed in Fig. 2 and causing the pinion 17 to bear against the bearing member 47, 35 and the frictional contact thus established is sufficient to maintain the desired position of the mechanism subject to change by manipulation of the operating handle.

For the purpose of rigidifying the structure, I 40 provide means for supporting the fuel supply pipe 13 within the housing 16. Thus, the vertical flanges 23 and 25 of the housing are cut away at their lower edges to provide a clearance between the lower horizontal flange 23 and the vertical flanges to form, in effect, horizontally spaced notches 55 and 56 respectively, for snugly receiving the pipe to hold the same against vertical movement. An angular bracket 57 is secured by bolts 58 to the inner face of the body 21 of the 50 housing and an outer flange 59 of the bracket embraces the fuel supply pipe 13 to prevent horizontal movement thereof out of position within the housing.

From the foregoing description, it will be evident that I have provided an oil burner mechanism which is simple and sturdy in construction, inexpensive to manufacture and dependable in operation. The parts of the mechanism are relatively few in number and provide a compact readily assembled unit in which every element is efficiently utilized.

I claim as my invention:

1. In a burner mechanism of the character described, a burner bowl providing a peripheral fuel trough and having a hollow interior open toward the bottom, a member bridging the upper part of said bowl, and a vertical sheet metal standard having a head portion centrally supporting said bowl and including an upper horizontal flange 70 secured to said member, said head portion having flanges at its side edges engaging with the sides of said bowl and providing additional connection between the standard and bowl.
2. In a burner mechanism of the character 75

described, an annular burner bowl, and a vertical thin metallic standard of channel-shape axially supporting said bowl near its upper margin, the body of said standard being substantially narrower than said bowl and having means at its upper end extending laterally of the body rigidly secured to the lower margin of the bowl at diametrically opposite sides thereof.

3. In a stove structure of the character described, a substantially box-shaped housing including a vertical body plate having a pair of spaced vertically extending lateral flanges and a pair of spaced horizontally extending lateral flanges, aligned guiding slots in said horizontally extending flanges, a burner and an elongated supporting standard therefor slidably mounted in said slots, a horizontally extending fuel supply pipe connected with said housing and having an extensible connection with said burner, said 10 vertically extending flanges being cut away at their lower edges to form notches which cooperate with the lowermost horizontal flange to engage said pipe and prevent relative vertical movement between said housing and pipe, means secured to said housing and engaging said pipe to prevent relative horizontal movement of said pipe, means fixedly connecting said housing to the stove structure, and means operable to move said standard and burner vertically.

30 4. A liquid fuel stove structure comprising, in combination, burner mechanism embodying a supporting structure including a pair of substantially spaced horizontal plates having axially aligned apertures therein spaced rearwardly of the forward margins of the plates and a vertical member rigid with said forward margins said member including an aperture in line with the axes of said aligned apertures and having bearing means rigid therewith and spaced rearwardly 35 therefrom, a burner and an elongated standard centrally supporting said burner and slidably mounted in said aligned apertures, an elongated element passing through the aperture in said member into coacting relation near its rear end with said bearing means and having means on its forward end for manually operating the same, means fixed upon the rear end of said element and engaging said standard for moving the latter vertically, a horizontal fuel pipe lying for- 40 wardly of the axis of said standard and having an upright extensible connection with said burner, means coacting with said vertical member to engage a substantial longitudinal portion of said fuel pipe at a plurality of diametrically opposite sides thereof to prevent relative horizontal or vertical movement between the pipe and said supporting structure during operation of the mechanism, and means fixedly connecting said supporting structure to the stove structure.

60 5. In a stove structure of the character described, a supporting structure including vertically spaced guiding elements, a burner and an elongated vertical supporting standard slidably mounted in said guiding elements, rotary means including an elongated shaft and an element in engagement with said shaft and operable to impart reciprocal movement to said burner and standard, a stationary abutment in axially fixed

relation intermediate the ends of said shaft, resilient means bearing against said abutment with force applied longitudinally of the shaft and serving to create frictional resistance to rotation in said rotary means to maintain the same and thereby said burner and standard in any given adjusted position, and means fixedly connecting said supporting structure to the stove structure.

5 6. In a stove structure of the character described, a supporting structure fixedly connected 10 to the stove structure, a burner and an elongated vertical supporting standard therefor slidably mounted in said supporting structure, a rack formed on said standard, manually operable means including a transversely extending rotary 15 shaft and a pinion fixed upon said shaft and engaging said rack to reciprocate said standard upon rotation of said shaft, means providing a bearing for said shaft and also a friction surface abutment for the adjacent face of said pinion, 20 and means operating to maintain continuous frictional engagement between said friction surface abutment and said adjacent face of said pinion for retaining the pinion in any given position of adjustment against downward force exerted 25 by the weight of said burner and said standard until said manually operable means is operated to rotate said shaft and said pinion.

7. A liquid fuel stove structure comprising, in combination, burner mechanism embodying a 30 supporting structure including a pair of substantially spaced horizontal plates having elongated axially aligned apertures spaced substantially rearwardly of the forward margins of the plates, a vertical plate rigid with said forward margins 35 and having an aperture axially disposed on a line with the axes of said aligned apertures, means rigidly supported by said vertical plate and including a bearing part substantially spaced rearwardly from the latter plate but lying forwardly 40 of said aligned apertures, a burner and a flattened elongated standard centrally supporting said burner and slidably mounted in said aligned apertures, a horizontally extending fuel supply pipe connected with said supporting structure and 45 having an upwardly extending connection with said burner, said standard having a longitudinal slot of predetermined length and breadth and a toothed rack on that longitudinal edge of the slot which is nearest the axis of the gravitational 50 and frictional forces arising during movement of the mechanism, a rotatable shaft having operating means on its forward end and passing through the aperture in said vertical plate and being supported near its rear end by said bearing part, 55 the extreme rear end of said shaft extending into said longitudinal slot in the standard and having a coaxial pinion rigid thereon lying in the plane of said standard and meshing with said rack for moving the standard vertically upon rotation of 60 the shaft, said pinion being stopped by engagement with the respective opposite ends of the slot after a partial revolution in either direction so as to limit vertical movement of said standard, and means fixedly connecting said supporting 65 structure to the stove structure.

WILLIAM T. BRADBURY.
